UNITED STATES PATENT OFFICE

95,005

DESIGN FOR A BLOUSE

Rose A. Weiss, New York, N. Y.

Application January 16, 1935, Serial No. 54,875

Term of patent 3½ years

To all whom it may concern:

Be it known that I, Rose A. Weiss, a citizen of the United States of America, residing in Manhattan, county of New York, and State of New York, have invented a new, original, and ornamental Design for a Blouse, of which the following is a specification, reference being had to the accompanying drawing, forming part thereof, wherein,

The vertical lines constituting the front panel of the blouse represent tucks, whereas the crossing bars at the front neckline represent cording.

I claim:

The ornamental design for a blouse, substantially as shown and described.

ROSE A. WEISS.
